UNITED STATES PATENT OFFICE.

CALEB BOND, OF RICHMOND, INDIANA.

WATER-WHEEL.

Specification of Letters Patent No. 28,826, dated June 26, 1860.

To all whom it may concern:

Be it known that I, CALEB BOND, of Richmond, in the county of Wayne and State of Ohio, have invented a new and useful Improvement in Water-Wheels; and I do hereby declare that the following is a full and exact description thereof, reference being had to the accompanying drawings, and to the letters of reference marked thereon,

10 made to form a part of this specification.

The nature of my improvement consists in the employment, and peculiar adaptation and arrangement of hinged auxiliary buckets; by means of which I am enabled to 15 adjust the water wheel as required, so as to secure the best effect from any given quantity of water.

With reference to the accompanying drawings, Figure 1, is a perspective view. Fig. 20 2, a sectional view of the main wheel. Fig. 3, a plan of main wheel with top plate removed. Figs. 4, and 5, a sectional view and plan of auxiliary wheel.

With reference to the construction, A, is 25 the main shaft and for purposes of description the end on which is placed the gear B, will be denominated the upper end, though in the practical working of the wheel it is not necessarily so, as the wheel may be arranged either end up or in a horizontal position. Upon the lower end of shaft A, is 30 arranged the curved descending and divergent surface c—d, terminating in a plane or level surface extending from d, to the periphery at b. On this surface are arranged the spiral partitions a, which are contracted gradually in depth, from their inner and upper ends to their lower and outer ends or 35 termination at b, the periphery of the wheel. To the top of these spiral partitions a, is 40 fitted an upper plate e, extending in an annular form from point f, to the periphery of the wheel. Thus are formed curved passages g. These passages g, taper 45 both in depth and width or thickness, from the center to the periphery, their larger dimensions in both particulars being next to the center opening f f. They also each make an entire circuit reaching the periphery on 50 the same radial line from which they start near the center.

The portions of the partitions a, within the circle of the opening f f, may both converge toward each other as they approach 55 the center and also decline in height. Oppo-

site the termination of each partition a, at the periphery is arranged a pivoted or hinged bucket or section, h, upon the adjacent partition, and this section h, is made adjustable by means of a pin x, and series 60 of holes as shown, or other suitable means, so as to contract the exit opening of the water passages or chutes, g, at that point to any required extent. By adjusting the capacity of the exit openings in this manner 65 I am enabled to use more or less water, proportionately to the amount of power required. That part of the passages g, where the sections h, swing has its top made parallel to the bottom so that the sections may fill 70 the space vertically and swing freely.

The two ends of shaft A, are sustained by pivots, or step and bearings in the usual manner.

A suitable flume C, is arranged in connection with the orifice f f, and the joint may be formed in any suitable manner as by means of the flange at f¹, on the wheel and the rim i, bolted to the flume and inclosing said flange with sufficient looseness to allow 80 it to rotate freely within.

D, is a gate by which to let on or shut off the water from the wheel.

B, is a gear wheel to transmit motion from the wheel to any machinery it may be 85 required to drive. An auxiliary wheel marked D¹, and shown separately in Figs. 4, and 5, may be used in connection with the above described main wheel or may be dispensed with as may best suit the case in 90 which the improvement may be required to be employed. This auxiliary wheel is composed of a rim encircling the periphery of the main wheel directly over against its exit openings, and is furnished with a series of 95 buckets arranged upon its inner surface. These buckets J, are curved and inclined backward at their lower end and occupy the space between the periphery of the main wheel and the rim of the auxiliary as completely as is consistent with their revolving freely around the main wheel, and terminate at the top against a flange turned inward upon the rim to which they are attached. The rim is furnished with arms k, and a central hub in which is fixed a shaft l, on which 100

is fixed a gear wheel m, from which the motion of the auxiliary wheel is transmitted in the usual manner. When the auxiliary wheel is employed its shaft may be 110

supported in bearings, or a step and bearings, in the usual manner, and a step may be arranged upon its hub or the end of its shaft to receive the pivot of the shaft of the 5 main wheel.

When the shaft A, is arranged horizontally a bearing *n*, may support it beyond the gate D, and the opposite end may then be extended to carry a gear wheel, crank or 10 pulley, to transmit its motion. When the full power of the wheel is required the sections *h*, are closed up against their respective partitions *a*, as shown at *o*, and the water being let on by opening the gate D, 15 passes down through opening *f f*, into and through the passages *g*, and escaping under pressure in the direction of the opening of passages *g*, at the periphery reacts upon the wheel to drive it in the opposite direction as 20 indicated by the arrow. The particular form of passages *g*, viz., inclining downward, diverging spirally, and contracting gradually, from the ingress to the exit openings, preserves the pressure unreduced by 25 friction comparatively if not entirely, to the exit, and so secures the best effect. When the auxiliary wheel *D*¹, is employed, the water escaping from the periphery of the first wheel falls upon the buckets *J*, of

the secondary wheel *D*¹, and drives that in 30 the opposite direction.

When less power is required than the full capacity of the first wheel, the adjustable sections *h*, are then adjusted so as to close up the exit openings of passages *g*, 35 proportionately to the amount of power required as illustrated by the positions represented, of two of said sections shown in Fig. 3, so reducing the discharge of water in a like proportion, and effecting a great saving thereof. The parts may be made of iron or any suitable material usually employed in manufacturers of the same class.

Having described the construction and operation of my improvement what I claim 45 as new and desire to secure by Letters Patent is—

In combination with the passages, *g*, the hinged auxiliary buckets, *h*, the whole being constructed and arranged to operate substantially in the manner as specified for the purposes described.

In testimony of which invention I have hereunto set my hand.

CALEB BOND.
